UNITED STATES PATENT OFFICE.

ISRAEL L. LANDIS, OF LANCASTER, PENNSYLVANIA.

SLICING-MACHINE.

SPECIFICATION forming part of Letters Patent No. 339,904, dated April 13, 1886.

Application filed January 5, 1886. Serial No. 187,687. (No model.)

To all whom it may concern:

Be it known that I, ISRAEL L. LANDIS, a citizen of the United States, residing at Lancaster, in the county of Lancaster and State of Pennsylvania, have invented certain new and useful Improvements in Slicing-Machines, of which the following is a specification, reference being had therein to the accompanying drawings.

10 My invention relates to slicers for food, such as meat, bread, vegetables, and fruit; and the object I have in view is to construct a machine the parts of which may be readily adjusted and removed for the purpose of cleansing, sharpening, and repairing, as will be hereinafter more fully set forth.

In the accompanying drawings, making part of this specification, Figure 1 represents a perspective of the machine with a portion at the 20 top broken away. Fig. 2 represents a perspective of the frame of the machine with guides and angle-iron attached. Figs. 3, 4, and 6 represent detached portions, as will be set forth. Fig. 5 represents a perspective of a guide and 25 retaining pin attached to its connecting-plate. Fig. 7 represents a modification that will be mentioned. Fig. 8 shows an end view of frame with slight modification.

In the figures, A A' represent the frame of 30 the machine, consisting of two end uprights connected by a suitable bottom.

B B represent two guide-pieces, which are provided with rectangular grooves facing each other. These guide-pieces are secured to the 35 frame A—one near its bottom and one near its top, and parallel to each other. These guide-pieces may be reversed end for end in case of wear, and they will work equally well.

D represents a sliding frame, which plays 40 in the grooves of the guide-pieces.

E represents the knife-plate, which is made of metal, and which is formed with rectangular flanges, through and by means of which it is secured within and to the frame D. This plate 45 has an angular lower edge, upon which the knife M is secured. The heads of the bolts that secure the plate E to the frame D are countersunk, so as not to obstruct the passage of the latter in the grooves of the guide-pieces B. 50 The threaded portions of these bolts pass through the slots a in the flanges of the plate E and into nuts which rest upon the said flange.

One side of the nut may rest against the plate E, so as to lock it on the bolt or prevent it turning thereon.

55

The knife-plate is provided on its sides with slots e e, through which screws or bolts pass to secure the knife to it. It will be seen that by this arrangement the knife may be adjusted when it wears and is ground down. The knife 60 may be moved upon the plate when necessary, or the plate itself may be moved. This plate serves, among other purposes, to give rigidity to the knife.

G represents the adjusting-board to regulate 65 the thickness of the slice to be cut by the machine. The upper edge of this board is at an angle to the frame, its angle corresponding to that of the knife and knife-plate.

H represents an angular bridge-piece provided with flanges, through which screws pass, by means of which it is secured to the frame D. This bridge-piece has in its face a slot, I.

L represents an angular plate, which is secured to the board G, its outer face portion 75 lying against the inner face of the bridge-piece H. Its contact-face may either be roughened or provided with a piece of rubber, as seen in Fig. 6. The plate L is provided with a loop, J, which protrudes through the slot I in bridge-piece H, and is there secured by means of a wedge, K, or by a wedge-pointed hook, k'. (Seen in Fig. 7.)

F represents a plate, which is secured to the board G, and which has secured to it or forming a part thereof a pin, f. This pin sets at an angle to the board G, as also to the frame D. The bottom sill of the frame D is provided with a hole inclined on the same angle with the piece L, for the reception and guidance of the pin f. 85 The board G is easily and quickly removed from the frame D by taking out the wedge, slipping the loop J out of its slot I, and then moving it endwise from the frame, the pin f at the same time being drawn out of the hole in 95 the sill. By moving the board endwise to or from the knife the throat formed between its edge and the knife is enlarged or diminished. The pin f keeps the lower forward end of the board firmly in place, while it is held in place 100 at the other end by the loop and wedge.

N represents an angle-iron secured to and in the mouth of the main frame. This iron is moved to or from the knife by set-screws play-

ing in slots in it. The knife shaves against the edge of this iron when cutting.

The frame D is moved to and fro in its bearings by means of a suitable handle connected 5 to the same.

In Fig. 8 the guide-pieces B B are slightly let into the frame A and there bolted. The adjustment of these pieces by their bolts may be made to adjust the knife-plate to or from 10 the angle-iron for regulating the cut.

Having thus fully described my invention, what I claim as new, and desire to secure by Letters Patent, is—

1. The combination, with the frame D, having 15 an oblique hole in the lower sill thereof, and the angular slotted bridge-piece H, secured thereto, of the regulating-board G, the angular plate L, provided with a loop extending through the slot in the bridge-piece, the wedge 20 K, the plate F, provided with the pin f, set at an angle thereto and entering the hole in the

sill, the plate E, and knife M, the plates L and F being attached to the regulating-board, substantially as and for the purpose specified.

2. The metallic knife-board E, slotted and 25 flanged and secured to the frame D, as set forth, in combination with the adjustable knife secured thereto, substantially as and for the purpose specified.

3. In a slicing-machine, the main support- 30 ing-frame, the slotted angle-iron, and the grooved guide-pieces, combined with a reciprocating frame consisting of an adjustable knife and knife-board, a regulating-board provided with an angular pin and looped plate, a bridge- 35 piece, and wedge, substantially as specified.

In testimony whereof I affix my signature in presence of two witnesses.

ISRAEL L. LANDIS.
